We claim the ornamental design for a bracket and sensor configuration for use in a vehicle door, as shown and described.

DESCRIPTION

FIG. 1 is a top right perspective view of the bracket and sensor configuration for use in a vehicle door;

FIG. 2 is a bottom left perspective view thereof;

FIG. 3 is a top view thereof;

FIG. 4 is a left side view thereof;

FIG. 5 is a front view thereof;

FIG. 6 is a right side view thereof;

FIG. 7 is a rear view thereof; and,

FIG. 8 is a bottom view thereof.

The dashed lines in various figures are for illustrative purposes only and form no part of the claimed design.
